UNITED STATES PATENT OFFICE.

TELFORD D. YOUNG, OF COLUMBUS, OHIO, ASSIGNOR OF ONE-HALF TO WILLIAM R. WEAKLEY, OF COLUMBUS, OHIO.

SAFETY GAS REGULATOR.

Application filed June 11, 1924. Serial No. 719,451.

To all whom it may concern:

Be it known that I, TELFORD D. YOUNG, a citizen of the United States, residing at Columbus, in the county of Franklin and 5 State of Ohio, have invented new and useful Improvements in Safety Gas Regulators, of which the following is a specification.

The present invention is directed to improvements in safety gas regulators.

10 The primary object of the invention is to provide a device of this character so constructed that it will not only regulate the flow of gas but will positively cut off the flow thereof when the pressure in the main 15 supply is removed.

A further object of the invention is to provide a device of this type which is extremely sensitive and positive in operation, and one which is simple in construction and 20 can be manufactured at a very small cost.

A still further object of the invention is to provide a regulator of this kind particularly designed for household use, but not necessarily limited to such use, the construction being such that should the supply 25 of gas in the main cease, further flow of gas to gas burners of illuminating fixtures, gas stoves or furnaces will be positively stopped, thus eliminating the possibility of 30 gas filling rooms, stoves or furnaces when the pressure is renewed, which occurrence often resulting in dangerous explosions and asphyxiation of the occupants of the dwelling.

35 I wish it understood that the disclosure is illustrative only and that the principle of my invention can be embodied in constructions other than the one specified herein.

40 In the accompanying drawing:—

Figure 1 is a vertical sectional view partly in elevation.

Figure 2 is a sectional view on line 2—2 of Figure 1.

45 Referring to the drawing 1 designates a casing, preferably circular in cross section and comprising upper and lower sections 2 and 3, respectively, the former having a top closure 4, while the latter is provided 50 with a base plate 5.

The section 3 is provided with an intermediate gas inlet 6 which communicates with the chamber 7, said chamber having formed in its bottom a conical valve seat 8 which is provided with a plurality of

ports 9, and co-operative with said seat is a conical valve 10, the stem 11 of which being slidable in the tubular guide 12 which depends from the valve seat 8. This stem has threaded in its lower end a headed coupling pin 13, the purpose of which will appear later.

Clamped between the respective securing flanges 14 of the sections 2 and 3 is the periphery of the diaphragm 15, which is formed from any material suitable for the purpose and to the center thereof is suitably fixed the upper end of the hollow rod 16, said rod being slidable in the vertically spaced guide bands 16' carried by the 60 adjacent end of the chamber 7. The lower end of this rod has threaded therein a headed coupling pin 17 for slidably and loosely engaging the slot 18 formed adjacent the inner end of the horizontally disposed lever 19, the outer end of said lever being pivotally connected to the bracket 20 supported interiorly of the lower section 3. This lever is also provided with a slot 21 with which the pin 13 co-operates.

The top 4 is provided with an interiorly threaded boss 22 in which is threaded the tube 23, there being a jam nut 24 on the tube and co-acting with the boss to hold the tube in proper adjusted positions. The lower end of the tube is provided with an annular inturned flange 25 for limiting the downward movement of the ball 26 carried by the upper end of the pin 27, said pin having its lower end threaded in the upper end of the rod 16. The top is further provided with a normally open valve 28, and leading therefrom is a pipe 29 which extends to the outside of the building to permit the escape of any gas which might from accidental causes enter the casing above the diaphragm 15.

80 The lower section 3 is provided with an outlet 30, which is disposed diametrically opposite the inlet 6 and from which the gas is piped to its point of use.

85 As shown in the drawing the valve 10 is seated, thereby cutting off the flow of gas from the main casing to the outlet 30, and in order to unseat the valve the hand wheel 31 fixed to the upper end of the tube 23 is rotated in a direction to elevate the tube and since the flange 25 engages the ball 26 the elevation of the tube will move the rod 16 upwardly and consequently the 90 105 110

lever 19 will be rocked, thereby raising the valve to an unseated position. In this manner the gas from the main may be let into the lower section of the casing for use. It will be understood that as long as the gas flows, its pressure, even though varying, will act upon the diaphragm 15 to keep the valve unseated, but as soon as the pressure ceases in the main the valve will be automatically seated and remain thus until unseated, as hereinbefore described. A screw 32 is engaged in the bottom or base plate 5, and in cases wherein the tube 23 is inaccessible, this screw may be operated to elevate the lever 19 which can be readily accomplished since the upper end of the same engages the pin 13. After the tube 23 or screw 32 has been manipulated to positively unseat the valve 10 they are adjusted to their normal positions to assure automatic operation of the device.

The upward movement of the tube 23 can be limited in any suitable manner to prevent injury to the diaphragm. Should the diaphragm become defective and permit gas to pass thereby the valve 28 may be closed until a new one is installed, it being of course necessary under such conditions that the tube 23 be elevated in order to hold the valve unseated.

What is claimed is:

1. A device of the class described comprising a casing, a diaphragm located in the casing, said casing having an inlet and outlet, a chamber in communication with the inlet and having a valve seat, guide bands carried by the chamber, a valve co-operative with the seat for controlling the flow of fluid from the inlet to the outlet, a lever connected with the valve and pivotally supported by the casing, and a rod slidably engaged in the guide bands and having its ends connected, respectively, with the diaphragm and lever.
2. A device of the class described comprising a casing having an inlet and a chamber in communication with the inlet, a valve seat in the chamber, a valve for the seat, a lever having one end pivotally connected to the casing and connected intermediate its ends with the valve, a diaphragm mounted in the casing, a rod connecting the free end

of the lever and the diaphragm, and means adjustably supported by the casing for actuating the rod, as and for the purpose 55 set forth.

3. A device of the class described comprising a casing having a fluid inlet and outlet, a chamber provided with a valve seat located in the casing, a valve co-operative 60 with the seat for controlling the flow of fluid from the chamber to the casing and outlet, guide bands carried by one end of the chamber, a lever having one end pivotally connected to the casing and connected intermediate its ends with the valve, a diaphragm operable in the casing, a rod 65 slidably in the guide bands and having its upper end secured to the diaphragm and its lower end pivotally connected with the free end of the lever, said lever and rod serving to control the movement of the valve with respect to the seat upon actuation of the diaphragm by fluid pressure, and independent adjustable means for lifting the 70 valve when the fluid pressure ceases to act upon the diaphragm.

4. A device of the class described comprising a casing having a fluid inlet and outlet, a chamber located in the casing and 75 having a valve seat, a valve co-operative with the seat for controlling the flow of fluid from the chamber to the casing and outlet, said chamber having guide bands 80 carried thereby, a lever pivotally supported in the casing and connected with the valve, a diaphragm mounted in the casing, a rod 85 slidably in the guide bands and having its upper end secured to the diaphragm and its lower end pivotally connected with the 90 lever, said lever and rod serving to control the movement of the valve with respect to the seat upon actuation of the diaphragm by fluid pressure, a tube adjustably supported by the top of the casing and having 95 a sliding connection with the rod, said tube when moved vertically in an upward direction acting to lift the rod and thus the valve from its seat through the medium of 100 said lever.

In testimony whereof I have hereunto set my hand.

TELFORD D. YOUNG.
